UNITED STATES PATENT OFFICE.

GILLISPA V. BOOCO AND JOSEPH W. HENAUT, OF LEADVILLE, COLORADO.

EXPRESS OR MAIL PROTECTION CAR.

SPECIFICATION forming part of Letters Patent No. 728,078, dated May 12, 1903.

Application filed January 17, 1903. Serial No. 139,412. (No model.)

To all whom it may concern:

Be it known that we, GILLISPA V. BOOCO and JOSEPH W. HENAUT, citizens of the United States, residing at Leadville, in the county of Lake and State of Colorado, have invented certain new and useful Improvements in Express or Mail Protection Cars; and we do hereby declare the following to be a full, clear, and exact description of the invention, 10 such as will enable others skilled in the art to which it appertains to make and use the same.

This invention relates to railway-cars, and contemplates the provision of improved means more especially designed for use in connection with express and mail cars for protection thereof and of the entire train against assault and burglary.

The nature of the invention will be readily comprehended, reference being had to the 20 following detailed description and to the accompanying drawings, illustrating the invention in its preferred form, it being understood that various modifications may be made therein without departing from the spirit of the invention as defined by the concluding claims.

In the drawings, Figure 1 is a side elevation of one end of a car equipped with the invention. Fig. 2 is an end view of the equipped car, full and dotted lines showing 30 the different positions of the parts.

Referring to the drawings by numerals, 1 denotes the car, which may be of the usual construction. It will be understood that the invention may be applied to a specially-35 provided car, in which case the car is preferably attached to the train next to the express or mail car or as close as possible thereto, or the invention may be applied to the express or mail car, this being readily accomplished without 40 material modification of the car structure.

In each side 2 of the car is a preferably rectangular opening 3, and at each opening is a box 4, the outer wall 5 of which in the normally retracted position of the box is flush 45 with the side of the car and completely fills the opening. The box is closed at all points except the inner side, which opens to the interior of the car, whereby access to the box is afforded.

50 At the bottom of each box are strips 6, which serve to strengthen said bottom, and said strips occupy guide-grooves 7 in the bottom

8 of the car, as shown more clearly in Fig. 1. The boxes are constructed, preferably, of steel to resist the penetration of bullets, and in the front 5 and sides 9 are loop-holes 10 for observation and the discharge of firearms from within.

The boxes are extended from the sides of the car by the following means: Pivoted by a pin 11 to an ear or ears on the car-floor is a lever 12, having at its outer or free end a handle 13. A link 14 is pivoted by a pin 15 at one end to the lever, and its other end is pivoted, by means of a pin 16, to the floor of the box. In the normal retracted position of the box the lever is in the upright position. (Shown by dotted lines in Fig. 2.) By moving the lever in the direction indicated by the arrow the box is moved to the extended position, (shown in full lines in Fig. 2,) the lever assuming a horizontal position when the box is fully extended. The link 14 is pivoted to the lever near the pivotal point of the latter, thereby securing a good leverage and effecting the movement of the box with the exercise of little power. Obviously the means employed enables the extension of the box with the minimum loss of time—an important advantage in the event of an assault. When extended, the box is supported by the strips 6 and also by the link connection with the lever. The box being extended, the occupant may have a full view along the length of the train through the side loop-holes and 85 of the area in front of the box through the front loop-hole.

Inasmuch as it is frequently necessary to distinguish between members of the train-crew and the persons committing the assault 90 there is provided a light 17, mounted on a supporting-rod which is slidable in a socket 18, provided in the upper portion of the box. It will be understood that the light is elevated when the box is extended, and by its 95 location and superior height a large area is lighted, enabling the occupant of the box to see the situation and direct his firearms against the proper persons.

We claim as our invention—

1. A railway-car having side openings, a bullet-proof box occupying each opening and mounted to be extended beyond the side of the car, and to be retracted to bring its outer

wall flush with the car-wall, and means for moving the box said means consisting of a swinging lever pivoted to the car-floor and a link connecting the lever and box.

5 2. A railway-car having side openings, a bullet - proof box occupying each opening, strengthening-strips at the bottom of the box, guide - grooves in the car - bottom for said strips, and means for moving the box to extended and retracted positions.

10 3. A railway - car carrying bullet - proof boxes mounted to be extended beyond the

sides of the car and provided with loop-holes at the front and sides, and a telescoping support for a light adapted to be extended above 15 the box when the latter is extended.

In testimony whereof we affix our signatures in presence of two witnesses.

GILLISPA V. BOOCO.
JOSEPH W. HENAUULT.
